Halsted & Ackerman,
Try Square & Bevel,
No 13,127, Patented June 26, 1855.

UNITED STATES PATENT OFFICE.

J. S. HALSTED AND C. J. ACKERMAN, OF NEW YORK, N. Y.

CARPENTER'S MITER AND BEVEL SQUARE.

Specification of Letters Patent No. 13,127, dated June 26, 1855.

To all whom it may concern:

Be it known that we, J. S. HALSTED and C. J. ACKERMAN, of the city, county, and State of New York, have invented a new and useful Implement or Tool for Carpenters and Jointers, said implement to be used for forming the joints of window and door casings and work of a similar nature; and we do hereby declare that the following is a full, clear, and exact description of the same, reference being had to the annexed drawings, making a part of this specification, in which—

Figure 1, is a view of one of the joints of a window or door casing. Figs. 2 and 3 are views of the ends of the top or head piece and side piece, with the implement or tool applied to them showing its use. Fig. 4, is a transverse section either of the top or side piece with the implement or tool applied to it.

Similar letters of reference indicate corresponding parts in the several figures.

This invention relates to a new and useful implement or tool for forming the joints of window and door casings and work of a similar nature which now require the use of several tools, such as the square, bevel, trying square, etc.

The nature of the invention consists in the peculiar construction of the implement as will be presently shown and described, whereby the joints may be "laid out" or marked in an accurate and expeditious manner.

A, Figs. 2, 3 and 4 represents the handle of the implement, and B, represents the blade. The handle may be made of metal having for convenience a slot (a) made in it for the fingers to pass through. The blade may be made of steel similar to those of the ordinary trying squares, and the blade is attached to the handle at right angles with it in the same manner as a trying square. The inner edge of the handle A, is provided with a ledge or flanch (b) which projects outward beyond each side of the handle as shown in Fig. 4, and both ends of the handle is cut or beveled at an angle of 45° as shown in Figs. 2 and 3. The lower end of the upper bevel is in line with the lower edge of the blade B.

In the outer edge of the handle A, there is a slot in which a steel blade C, is fitted. The upper end of this blade is attached to

the upper part of the handle A, by a screw (c) so that the blade may be moved in and out from the handle and set in line with the bevel at the upper end of the handle, or, at an angle of 45° as shown in Fig. 3. 60

The implement or tool thus constructed is used in the following manner. D, Figs. 1 and 2, represents one of the side pieces or stiles of a window or door frame, and E, Figs. 1 and 3 represents the head or top piece of the frame. These pieces are made more or less ornamental in all cases, the inner edges of the pieces having beads or moldings formed on them, as represented by (d) and in expensive houses carved work 65 is used. The pieces are also formed with recesses or grooves on their face sides arranged in various ways. The joints of the frames are never formed by a simple "miter" as the least shrinkage of the frame 70 would show very plainly opening the joints and leaving an unsightly space. A zig zag joint is formed as indicated in red Fig. 1.

In order to "lay out" or mark the joint the ends of the pieces are first squared. 80 The side pieces or stiles D, are marked or laid out by getting the point (e) on the molding (d) by actual measurement, the flanch or ledge (b) on the inner edge of the handle A is then fitted in the groove or 85 kerf formed by the bead or molding (d), and the handle is moved till the point (e) touches the upper edge of the handle see Fig. 2. The two lines (f) (g) are then drawn, (f) being a miter or an angular line 90 of 45°, and the line (g) a horizontal one. The vertical line (h) is obtained without marking as it is on the shoulder (i), of a recess in the face of the stile. Thus by a single application of the implement the side 95 pieces or stiles are marked.

The head pieces E, are marked or "laid out" as shown in Fig. 3, the point (e) being obtained the inner edge of the handle is placed against the shoulder (i) of the recess, and the blade C, is adjusted in line with the bevel at the upper end of the handle A, and the implement is moved till the point (e) touches the upper edge of the blade C, the miter line (j) across the head 105 or molding, and a point (k), on the shoulder (i), is thereby obtained, and by reversing the implement the line (l), obtained at right angles with the shoulder (i). The ends when cut according to the lines above 110

described will form when the pieces are adjusted or put together the joint as shown in Fig. 1.

The implement or tool may be used with 5 advantage in all cases where joints are formed in a similar manner or where straight and diagonal or miter lines are to be drawn in connection with each other.

Having thus described our invention what 10 we claim as new and desire to secure by Letters Patent, is—

The construction of the implement as herein shown and described, viz, having a ledge or

flanch (d) projecting on each side of the inner edge of the handle A, the upper and lower 15 ends of said handle being cut or beveled at an angle of 45°, the handle being provided with a blade B, which is attached at right angles to it, and also provided with an adjustable blade C, as herein shown, and for 20 the purpose as set forth.

JONAS S. HALSTED.

CORNELIUS J. ACKERMAN.
